US0D1021501S

(12) **United States Design Patent** (10) Patent No.: **US D1,021,501 S**
(45) Date of Patent: ** Apr. 9, 2024

(54) **COFFEE MACHINE**

(71) Applicant: **LG ELECTRONICS INC.**, Seoul (KR)

(72) Inventors: **Hyunggon Ryu**, Seoul (KR); **Hyejin Kim**, Seoul (KR); **Junhee Yeo**, Seoul (KR); **Sung-Gul Hwang**, Seoul (KR)

(73) Assignee: **LG ELECTRONICS INC.**, Seoul (KR)

(**) Term: **15 Years**

(21) Appl. No.: **29/852,654**

(22) Filed: **Sep. 8, 2022**

(30) **Foreign Application Priority Data**

May 20, 2022 (KR) 30-2022-0020154

(51) **LOC (14) Cl.** **07-01**

(57) **CLAIM**

We claim the ornamental design for a coffee machine, as shown and described.

DESCRIPTION

FIG. 1 is a front perspective view of a coffee machine showing our new design;

FIG. 2 is a bottom perspective view thereof;

FIG. 3 is a front elevation view thereof;

FIG. 4 is a rear elevation view thereof;

FIG. 5 is a left-side elevation view thereof;

FIG. 6 is a right-side elevation view thereof;

FIG. 7 is a top plan view thereof;

FIG. 8 is a bottom plan view thereof; and,

FIG. 9 is a front elevation view thereof, shown in condition of use with the legs adjusted in height. The broken lines depict portions of the coffee machine that form no part of the claimed design.

1 Claim, 9 Drawing Sheets
